IRA B. HART, OF ST. LOUIS, MISSOURI, ASSIGNOR TO THE RECIP-ROTO ENGINE COMPANY, OF ST. LOUIS, MISSOURI, A CORPORATION OF DELAWARE.

ROTARY PUMP AND ENGINE.

1,408,292.

Specification of Letters Patent. Patented Feb. 28, 1922.

Application filed July 8, 1920. Serial No. 394,704.

To all whom it may concern:

Be it known that I, IRA B. HART, a citizen of the United States of America, a resident of the city of St. Louis, in the State of Missouri, have invented certain new and useful Improvements in Rotary Pumps and Engines, of which the following is a full, clear, and exact description, reference being had to the accompanying drawings, forming a part of this specification.

This invention relates to improvements in rotary pumps and engines, and the novel features of the invention are especially adapted for use in rotary pumps. The main object of the invention is to produce a simple and efficient automatic valve device adapted to prevent free and open communication between the inlet and outlet ports of a pump or engine.

More specifically stated, the particular structure herein described comprises an eccentrically mounted piston and a pivot connecting the piston to a rocker arm. The piston moves away from an inlet port and toward an outlet port to provide for the admission and discharge of fluid, and owing to the peculiar manner in which it is mounted in the cylinder, the piston also swings from an extreme position near the outlet port to an initial position near the inlet port. During the last mentioned movement of the piston, said piston is separated from the circular inner face of the cylinder, and the passage from port 8, to port between piston and cylinder, should be closed to prevent free communication between the ports. The invention therefore includes a simple automatic valve device, preferably a pressure actuated check valve adapted to contact with the piston and cylinder while the piston is passing from one extreme position to the other, thereby preventing communication between the inlet and outlet ports.

Fig. I is a vertical section illustrating the invention applied to a pump.

Fig. II is a section taken approximately through the center of the structure shown in Fig. I, with the piston shown in elevation.

To illustrate the invention, I have shown a pump comprising a cylinder A provided with flat side walls 1 and 2. The wall 1 may be in the form of a head attached to the cylinder, and the wall 2 may be a partition dividing the cylinder into two com-

partments. Each compartment contains a piston and a rocker arm which will be hereafter described, and since any desired number of compartments may be employed, a description of the elements in one cylinder 60 compartment will fully disclose the invention.

A rotary power shaft 3 extends through the cylinder and is located at the center thereof. An eccentric 4 lies between the flat 65 side walls of the cylinder, and this eccentric is fixed to the rotary shaft 3. An annular piston P is mounted on the eccentric 4 and provided with flat side faces adapted to cooperate with the flat side walls 1 and 2 70 to prevent leakage between the piston and said side walls. A cylindrical pivot member 5, extending from the annular piston P, is embraced by a head of a rocker arm 7 pivotally supported by a rod or shaft 8. The 75 head 6 is equal in width to the piston P so as to cooperate with the flat walls 1 and 2, thereby preventing direct communication between the intake chamber 9 and the discharge chamber 10.

Inlet and outlet ports 11 and 12, respectively, are formed at opposite sides of the head 6 to provide for the admission and discharge of fluid. The eccentric 4 turns with the power shaft 3, as indicated by an 85 arrow near the center of Fig. I, so a rotary motion is imparted to the eccentric while the annular piston P oscillates about the center of the pivotal connection 5. The piston P has a peculiar motion relative to 90 the circular inner face of the cylinder. When the parts occupy the position shown by dotted lines in Fig. I, the piston P contacts with the circular cylinder face 13 at a point near the inlet port 11, and if a rotary 95 motion is imparted to the eccentric 4, the point of contact between piston and cylinder will approach the outlet port 12. In response to a motion of this kind, a body of fluid will be drawn through the inlet port 100 11 and a body of fluid will be discharged through the outlet port 12.

When the piston P reaches the position shown by full lines in Fig. I, the last mentioned body of fluid will have been discharged through the 105 outlet port 12. A continued rotary motion of the eccentric will displace the piston P from a point of contact adjacent the outlet port 12, as shown by dotted lines, and during this motion the piston is entirely free of con- 110

tact with the circular inner face 13 of the cylinder, and the fluid under pressure in the discharge chamber 10 will then tend to flow back into the cylinder. Since the piston 5 ton P thus does not prevent free communication between the inlet and outlet ports during the period just referred to, I provide a simple automatic valve device which is effective during this period.

10 As an illustration of a suitable valve, I have shown a blade 15 pivotally interlocked with the piston and having a free edge adapted to engage the circular inner face of the cylinder. The circular outer face of the 15 piston P is provided with a recess having side walls 16 and 17 which diverge from a cylindrical pocket 18 to the outer face of the piston, and the blade 15 is provided at its inner end with an enlarged cylindrical portion 19 closely fitted to the wall of pocket 18. The blade 15 is thus pivotally interlocked with the piston, and the axis of this 20 pivotal connection is parallel with the axis of shaft 3. The length of blade 15 is equal 25 to the width of piston P, so the end edges of blade 15 will engage or lie very close to the flat side walls 1 and 2.

When the apparatus is used as a pump, the valve blade 15 preferably extends from 30 its pivotal connection to a point near the outlet port 12. This pivoted blade is exposed to the fluid pressure at the outlet port and it forms an automatic pressure actuated check valve, which prevents free communication between the outlet and inlet ports 35 while the piston is moved from the position shown by full lines in Fig. I to the position shown by dotted lines. At the beginning of this movement, the fluid under pressure at 40 the outlet port 12 will enter a small pocket 20, which may be formed by cutting away a portion of the free edge of the valve blade, and this fluid under pressure will then enter between the blade 15 and the wall 16 of the 45 blade-receiving pocket, so as to force the blade into firm engagement with the circular inner face of the cylinder. As the motion of the piston continues, the free outer edge of blade 15 will remain in contact with the 50 cylinder and the parts will eventually occupy the positions shown by dotted lines. Thereafter, the fluid in the crescent-shaped 55 space between the piston and cylinder will be placed under pressure, and when this pressure becomes greater than the fluid pressure at the outlet port 12, the valve blade 15 will be forced back into the recess between the diverging walls 16 and 17 so as to permit the outgoing liquid to escape 60 through the outlet port 12.

It will be understood that the valve device is closed by fluid pressure on its outlet side and that it remains closed until the piston again begins to force fluid through the 65 outlet port.

Owing to the peculiar manner in which the piston is mounted, the free outer edge of the pivoted valve 15 will slide on the circular inner face of the cylinder, and even though this sliding motion results in slight 70 wear of the valve or cylinder, the valve will continue to perform its function, for it is held in contact with the cylinder by fluid pressure and thereafter opened by the pressure of fluid on the inlet side of the valve. 75 Furthermore, the valve blade does not strike hammer blows on the cylinder. The valve is held in a closed position by fluid pressure until it is opened by the pressure of the outgoing fluid on the inlet side of the valve. 80

When the blade 15 occupies the position shown by full lines in Fig. I, there is preferably a slight space between said blade and the wall 16, the object being to provide a space for foreign matter which would otherwise tend to prevent the blade from occupying the position shown by full lines. 85

I claim:

1. The combination of a cylinder, a piston in said cylinder, a rotary member on 90 which said piston is eccentrically mounted, said cylinder having inlet and outlet ports and said piston being movable from a point on the cylinder adjacent said outlet port to a point on the cylinder adjacent said inlet 95 port, and a valve pivoted to said piston and adapted to contact with said cylinder while the piston is moving from one of said points to the other.

2. The combination of a cylinder, a piston in said cylinder, a rotary member on which said piston is eccentrically mounted, said cylinder having inlet and outlet ports and said piston being movable from a point on the cylinder adjacent said outlet port to a point on the cylinder adjacent said inlet port, and a check valve whereby said outlet port is closed while the piston is moving from one of said points to the other, said check valve being pivoted to said piston and exposed to the fluid pressure at said outlet port so as to occupy its closed position in response to said fluid pressure, and said pivoted check valve being movable to its open position in response to the pressure of fluid 115 passing to said outlet port on the inlet side of the valve. 110

3. The combination of a cylinder, a piston in said cylinder, said piston being smaller in diameter than the internal diameter of 120 said cylinder, a rotary member on which said piston is eccentrically mounted so as to cooperate with the circular inner face of said cylinder, a rocker-arm pivoted to the eccentrically mounted piston, said cylinder 125 having inlet and outlet ports at opposite sides of said rocker-arm, said eccentrically mounted piston being movable away from the inlet port and toward the outlet port to provide for the admission and discharge of 130

fluid, said eccentrically mounted piston being also movable from a position adjacent said outlet port to a position adjacent said inlet port, and a valve pivoted to said piston 5 ton and having a free edge adapted to contact with said cylinder to close communication between said ports during the last mentioned movement of the piston.

4. The combination of a cylinder, a piston 10 in said cylinder, said piston being smaller in diameter than the internal diameter of said cylinder, a rotary member on which said piston is eccentrically mounted so as to cooperate with the circular inner face of 15 said cylinder, a rocker-arm pivoted to the eccentrically mounted piston, said cylinder having inlet and outlet ports at opposite sides of said rocker-arm, said eccentrically mounted piston being movable away from 20 the inlet port and toward the outlet port to provide for the admission and discharge of fluid, said eccentrically mounted piston being also movable from an extreme position adjacent said outlet port to an initial position 25 adjacent said inlet port, and an automatic pressure actuated check valve whereby said outlet port is closed during the last mentioned movement of the piston, said check valve being pivoted to said piston and provided with a free edge adapted to contact 30 with said cylinder, and said check valve being exposed to the fluid pressure on its outlet side.

5. The combination of a cylinder, a piston 35 ton eccentrically mounted in said cylinder, a rocker-arm extending from said piston, said cylinder having inlet and outlet ports at opposite sides of said rocker-arm, said piston having a circular outer face provided 40 with a recess, and a pivotally mounted check valve located in said recess and having a free outer edge movable into and out of engagement with said cylinder.

6. The combination of a cylinder, a piston 45 in said cylinder, a rotary member on which said piston is eccentrically mounted, said cylinder having inlet and outlet ports and said piston being movable from a point on the cylinder adjacent said outlet port to a point on 50 the cylinder adjacent said inlet port, said piston having a circular outer face provided with a recess, and an automatic pressure actuated check valve in said recess, said check

valve comprising a blade pivotally interlocked with said piston and having a free 55 outer edge adapted to engage said cylinder in response to pressure on one side of said blade.

7. The combination of a cylinder, a piston in said cylinder, a rotary member on which 60 said piston is eccentrically mounted, said cylinder having inlet and outlet ports and said piston being movable from a point on the cylinder adjacent said outlet port to a point on the cylinder adjacent said inlet 65 port, said piston having a circular outer face provided with a recess, and an automatic pressure actuated check valve in said recess, said check valve comprising a blade pivotally interlocked with said piston and having 70 a free outer edge adapted to engage said cylinder in response to pressure on one side of said blade, the length of said blade being equal to the width of said piston and the axis of the blade pivot being parallel to the 75 axis of said piston.

8. The combination of a cylinder, a piston eccentrically mounted in said cylinder, a rocker-arm extending from said piston, said cylinder having inlet and outlet ports at opposite sides of said rocker-arm, and a valve 80 adapted to close one of said ports, said valve being interposed between said piston and cylinder and said valve being movable relative to the piston and cylinder, one of the last 85 mentioned parts having a recess in which the interposed valve is normally seated, and a portion of said valve being separated from a wall of said recess to provide a space between said wall and valve. 90

9. The combination of a cylinder, a piston eccentrically mounted in said cylinder, a rocker-arm extending from said piston, said cylinder having inlet and outlet ports at opposite sides of said rocker-arm, said piston having a circular outer face provided 95 with a recess, and a pivotally mounted check valve located in said recess and having a free outer edge movable into and out of engagement with said cylinder, a portion of 100 said valve being separated from a wall of said recess to provide a space between said wall and valve.

In testimony that I claim the foregoing I hereunto affix my signature.

IRA B. HART.
